TELEGRAPHIC PRINTING MECHANISM

Alfred Vischer, Jr., Ridgewood, N. J., assignor to
The Financial Press Companies of America,
Boston, Mass., a trust of Massachusetts

Application April 6, 1932, Serial No. 605,614

16 Claims. (Cl. 197—48)

This invention relates to high speed printing mechanisms of the type adapted to print a series of letters or other characters across a sheet or tape in rapid succession in response to signals transmitted from a remote point. It has particular reference to a printer of this character employing a rotatable printing wheel which is shifted across the paper at letter-space increments but restored with one quick movement and is rotated continuously in the same direction under control of an escapement to select the characters to be printed.

It has been a primary object of the invention to so construct and arrange the various parts as to speed up the operation of such a printer so that a considerably greater number of characters may be printed within a given time interval than has heretofore been possible. Among the specific features of the invention by which this object is attained is the provision of an improved form of escapement permitting more rapid oscillation of the escapement pawl which controls the rotation of the printing wheel. Another feature toward this end is the mounting of the printing wheel upon its supporting shaft in an improved way. The construction is such that the wheel may be more readily shifted across the paper and yet is arrested in definite character selecting positions so that printing may be effected in a straight line even at high speeds. A still further feature is the provision of an improved dash-pot construction which permits rapid return of the type wheel carrier, after a line has been printed, and to position it for the printing of the next line, without undue vibration or jar upon the parts.

Other features and advantages of the improved construction will be made apparent from the detailed description of one illustrative embodiment of the invention which will now be given in conjunction with the accompanying drawings in which:

Figure 1 is a front, elevational view of the printing wheel driving and shifting mechanism.

Figure 2 is a top plan view of the same.

Figure 3 is a detail view, in elevation, of the escapement pawl with the casing in which it is mounted shown in section.

Figure 4 is an enlarged detail view in section along the line 4—4 of Figure 3.

Figure 5 is a detail view in section along the line 5—5 of Figure 4.

Figure 6 is an enlarged bottom view of the escapement pawl, as viewed along the line 6—6 of Figure 3.

Figure 7 is an enlarged detail view of the dash-pot construction, largely in vertical section through the same.

Figure 8 is a sectional view along the line 8—8 of Figure 7.

Figure 9 is a vertical sectional view along the line 9—9 of Figure 1.

Figure 10 is a detail view in vertical section along the line 10—10 of Figure 7.

Figure 11 is a detail view in plan of the dash-pot construction.

Figure 12 is an enlarged sectional view through the type wheel unit.

Figures 13 and 14 are detail, sectional views along the lines 13—13 and 14—14, respectively, of Figure 12.

Figure 15 is a perspective view of certain parts of the escapement unit in disassembled relation.

Figure 16 is a sectional view through the magnet along the line 16—16 of Figure 2.

Figure 17 is a perspective view of a carriage return mechanism, and

Figure 18 is a detail view along the line 18—18 of Figure 2.

Referring now to the drawings there is provided a main frame 10 of suitable form and construction to support the various operating devices.

A motor 11 is provided to drive a main shaft 12 which serves as the driving source for the parts to be actuated. Through helical gearing 13 it provides the motive power for the rotation of the type wheel supporting shaft 14.

A friction clutch 15 is interposed in the driving connection to the shaft 14 so that while the shaft 12 is constantly driven so long as the machine is in operation the shaft 14 may be independently controlled and arrested in any desired position.

The extent of rotation of the shaft 14 is controlled by an escapement mechanism including an escapement wheel 16 secured to the shaft.

An escapement pawl 17 having projections or pallets 18 is adapted to be oscillated to carry these projections alternately into engagement with the teeth of the escapement wheel.

The pawl 17 is carried by an armature member 19, which may be regarded as a part of the pawl unit and which is formed of any suitable electro-magnetic material.

The armature may conveniently be formed as a flat stamping from stock, say about a tenth of an inch in thickness. Any suitable form of connection may be provided between the pawl and armature.

They may, for example, be provided with interengaging prongs and slots welded or otherwise permanently connected.

110

The pawl itself is preferably formed of non-magnetic material so that it will not tend to stick to the teeth of the wheel and will reduce flux leakage. The pallets 18 are preferably made of hardened tool steel or other suitable material.

At each end of the armature there is mounted a supporting member 20 formed of resilient material, preferably tempered spring steel. These members, as will be explained, serve to support the armature from a rigid portion of the machine and are adapted to permit a rapid oscillation of the pawl in response to electrical impulses. It has been found exceedingly difficult to provide a suitable support for the armature which will have the desired restoring action assisting in the rapid swinging of the armature and pawl to the opposite side when the current is reversed and at the same time will stand up under continual use over a long period and at a high speed. As will more clearly appear hereinafter the escapement pawl should be capable of receiving 40 to 60 complete oscillations per second in the transmission of messages at a high speed. To produce these rapid oscillations it is necessary that the armature be placed under a considerable force tending to centralize it, thus offsetting the inertia which would exist in a freely pivoted member. It has been found that the supporting members 20, if not properly applied, tend to work loose from the armature. Furthermore, when they are formed simply as stampings from sheet material it has been found that they very quickly give way to the strains imparted by the rapid oscillations and are soon sheared off. These difficulties have been overcome in the present construction.

In the first place the members 20 have been applied to the armature in an improved manner which tends to obviate working loose at the joints. Each member is provided at its inner end with a slot 21 which serves to divide it into forked portions adapted to straddle the end of the armature. There is also provided a button 45 or disc 22 cut in half after assembly to provide a slot 23 between the upper and lower portions to receive the member 20. This disc is received by a slot 24 cut into the end of the armature, the disc abutting against the inner end of the slot. The parts when assembled are held together by solder. This provides a connection which appears to have sufficient yield to absorb the strains incident to rapid oscillations. Now to overcome the shearing tendency referred to the members 20 are stamped from a thin ribbon of tempered, spring steel in lieu of being stamped from a flat sheet. In this way the scoring of the edges of the members which invariably results from a stamping operation will be avoided. It has been found that these minute score lines when left in the longitudinal edges of the member will form the starting point of a shear which in the course of a relatively brief period will work entirely across the member. By stamping the members from a narrow ribbon having just the width of the finished member smooth, rounded edges 25, shown on a magnified scale in Figure 4, may be provided along the longitudinal sides and these edges will be entirely free of score lines. The ribbon of material from which the members are formed may, if desired, be stamped or cut from a wider sheet but before being used to stamp out the parts 20 it should then be passed through suitable operations such as rolling or drawing

to make the edges into the smooth, rounded form shown. This will serve to eliminate any scoring that might have been produced in the original cutting or stamping operation. As a result of the construction and mounting of the members 20 in the manner explained the difficulties of breakage and separation previously encountered have been overcome.

For the purpose of suspending the armature the members 20 are provided with openings 26 adapted to receive special nuts kept from turning by square shoulders engaging the sides of the opening and in turn receiving small bolts or screws 27 passed through openings in a casing 28 surrounding the armature and suitably secured to a portion of the machine frame. A spacing collar 29 around each bolt serves to hold the armature in proper position. The armature, as is customary in devices of this character, is mounted between the poles of a permanent magnet 30 at the end of which the casing 28 is carried. Within the casing two laminated pole pieces 31 are so arranged that they serve to extend the poles of the magnet 30 inwardly to planes a short distance on either side of the armature. The ends of the pole pieces are divided to present two like poles on each side of the armature, one above and the other below the pivotal axis of the armature. A coil 32 surrounding the armature and inserted in the recesses between the upper and lower poles of the pole pieces is adapted to receive current impulses in accordance with signals sent out from suitable sending apparatus. These impulses are passed alternately in opposite directions through the coil and thereby temporarily magnetize the armature in one sense upon reception of one impulse and in the opposite sense upon the next impulse, in a manner well known. This reversal of the polarity of the armature causes it to oscillate upon its supports and correspondingly carries the projections 18 of the escapement pawl alternately into and out of mesh with the teeth on wheel 16. This brings about the desired control over the rotation of the shaft 14. It will be understood that, in accordance with the common practice, the shaft 14 is rotated always in the same direction and the escapement is so controlled that the extent of rotation permitted is just sufficient to bring the successive characters desired into printing position.

The characters to be printed are carried by a printing wheel 33 slidably mounted upon the shaft 14 but keyed thereto so as to rotate with the shaft. In view of the high speed with which the wheel is rotated from one position to the next, it is preferably formed of very light construction so that there is little inertia to overcome in setting it in motion and arresting it. It is important that the wheel should be capable of sliding easily along the shaft 14 so that it may be shifted step by step at letter space increments by suitable means, such as that disclosed in detail in my prior Patent No. 1,832,160, granted November 17, 1931. At the same time it is important that the wheel should always assume a very definite relation to the shaft 14 so that the characters will be printed in proper alignment upon a sheet or strip of paper. Wheel 33 is mounted upon a sleeve 331 which serves to unite the several parts of the slideable wheel unit. The sleeve is provided with a hub portion 332 over which is fitted a formed hub portion of the wheel disc. A screw cap or nut 333 engaging

a threaded portion at the end of the sleeve 331 serves to hold the wheel in fixed relation to the sleeve. The shaft 14 is provided with a keyway 34 with which inward extensions of key members 35 and 36 are adapted to cooperate. These key members are carried at opposite sides of the printing wheel disc and are so constructed as to provide a certain amount of play in the keyway 34; that is to say the extensions which enter the keyway are slightly less in thickness than the width of the keyway. This serves to provide the desired easy sliding of the wheel along the shaft. The key element 35 is positively clamped to the printing wheel and sleeve by means of the screw cap 333. The relation between the inner end of the element 35 and the wheel 33, therefore, is fixed. The key element 36, on the other hand, is carried loosely upon a hub portion 334 of the sleeve 331 so that a slight relative movement may take place between this key element and the wheel. A spring 39 is connected between a tab 40 struck up from a portion of the wheel and an eyelet 41 carried by the key element 36. The spring 39 thus tends to produce relative rotative movement between the wheel and key element 36. The extent of such movement, however, is limited by the amount of play between the key elements and the keyway 34. The construction is such that the inwardly projecting end of the element 35 will bear against one wall of the keyway while the inward projection of the element 36 will bear against the opposite wall of the keyway. Therefore, while a certain amount of play is permitted between the keys and keyway so as to permit an easy sliding action, the spring 39 will always tend to maintain the wheel in a definite relation to the groove in the shaft. In the rapid rotation of the wheel the play in the parts may tend to produce a slight lag between the wheel and the shaft. This lag, however, will be taken up by the spring 39 when the shaft comes to rest, as well as by the momentum of the wheel itself. Therefore, when the printing takes place a moment later, printing of the characters in proper alignment is insured.

By means of electrical circuits and devices well known in the art, or by means of the arrangement disclosed in the copending application of Herbert L. Paulding, S. N. 603,468 filed April 6, 1932, now Patent Number 1,957,076, May 1, 1934, a printing impulse which results in the operation of a platen and the subsequent shifting of the printing wheel to the next adjacent letter space position takes place automatically upon the lapse of a time interval slightly greater than that between successive impulses utilized in the control of the escapement mechanism. Thus, when a key is depressed at the control point, impulses are transmitted to the escapement mechanism at a definite frequency and when the final impulse of a series is sustained to an appreciably longer duration, and the wheel has reached its new setting, this reduction in frequency will cause an electro-magnet 42 to be operated to control the operation of a spring clutch 43. This clutch is released by the operation of a detent or disabling pawl 44 secured to a shaft 441 upon the energization of the electro-magnet 42, in the manner explained, this electro-magnet attracting an armature 442 secured to shaft 441. Upon rocking of the pawl 44, the clutch 43 and its connected shaft 45 will be released for operation by the drive shaft 12. Suitable helical gearing 46 may be provided between the shaft 12 and the left-hand member of the clutch 43 (Fig. 1). Rotation of the shaft 45 will bring about the reciprocation of a pair of racks 47, in the manner more fully explained in my prior patent, before-mentioned. Reciprocation of these racks will serve to shift a carriage 48 at letter space increments along a supporting shaft 49, this being accomplished by the engagement of a pair of pawls 50 with the teeth of the ratchet-toothed racks 47. The pawls 50 are pivotally mounted at 51 upon a portion of the carriage 48. An upwardly extending portion 52 of the carriage is forked to engage the opposite sides of a grooved portion 53 of the sleeve of the type wheel assembly. At its lower end the main frame of the carriage 48 is provided with a bearing 54 slidable along the shaft 45. This serves to position and guide the carriage in such a way that the prongs 52 will not bear against the bottom of the groove in the portion 53 of the type wheel unit and will consequently not interfere with the free rotation of the type wheel. It will be apparent, however, that through the connections explained the step-by-step movement of the carriage 48 will produce a corresponding shifting of the type wheel along its supporting shaft 14. It may be mentioned that rotation of the shaft 45 will bring about the operation of a printing platen, in a manner known in the art. Inasmuch as the operation of the platen forms no part of the present invention, however, this part of the mechanism has not been disclosed herein.

After a series of characters has been printed across a sheet of paper, (not shown) which is suitably supported in printing relation to the wheel 33, the wheel and the carriage 48 will be restored to the left-hand side of the machine (Fig. 1 and 2) and the paper will be line-spaced so that the printing of the next line across the sheet may be brought about. The return of the carriage for this purpose is produced by means of a spring 55 (Fig. 17) connected at one end to a stud 56 carried by a portion of the frame and connected at its opposite end to a lever 57. This lever at its upper end is connected to the carriage by means of the stud 51 and at its lower end is pivotally mounted on a frame 58 which in turn is pivotally mounted at 59 on a portion of the frame of the machine. The relation of the spring 55, lever 57, and frame 58 is such that the force tending to restore the carriage to the left-hand side of the machine is substantially constant at all times. In order to permit the spring 55 to function, it is necessary to lift the pawls 50 out of engagement with the racks 47. This is accomplished by means of an arm 60 (Fig. 18) carried by a sleeve 601 shiftable with the carriage assembly 48 but rockable with relation to the carriage. The arm 60 is provided with an inwardly extending key portion adapted to ride in a groove or keyway 61 provided in the shaft 49. While the carriage 48 is simply slidable longitudinally with the shaft, the arm 60 partakes of this longitudinal movement and is also rocked with the shaft, when the latter is rocked by means to be later explained. Upon rocking of the shaft the under surface of the arm 60 will engage rearwardly extending arms 62 of the pawls 50. Springs 63 normally draw the arms 62 upwardly to engage the pawls with the teeth of the racks 47. However, when it is desired to return the carriage toward the left, the arm 60 is simply rocked downwardly to engage the arms 62 and thus disengage the 150

pawls 50 from the racks. This allows the spring 55 to return the carriage and the printing wheel toward the left. (Figs. 1 and 2).
5 Rocking of the shaft 49 (Figs. 9 and 10) to disengage the pawls 50 in the manner explained is accomplished in the following manner: Upon the shaft 45 there is mounted a cam member having a projection 64 adapted upon each rotation of the shaft 45 to engage the lower end of a 10 two-armed floating lever 65. This lever is pivotally connected at 66 with a plate 67 secured to the shaft 49. Normally the rocking of the lever 65 will be an idle movement about the pivot 66. However, when it is desired to return the carriage to the left of the machine, the upper end of the lever 65 is held against inward movement by means of a projection 68 carried by the printing wheel shaft 14. The projection 68 corresponds with a blank position on the 20 printing wheel,—that is to say whenever the blank space on the printing wheel is brought opposite the printing platen, the projection 68 will be brought in line with the end of a member 69 pivotally mounted at the upper end of the 25 two-armed member 65. It will be apparent that under these conditions rocking of the member 65 by means of the projection 64 will cause the pivot 66 of the member to be shifted toward the right in Fig. 9. This will produce a rocking 30 of the plate 67 and shaft 49. This in turn will cause the pawls 50 to be disengaged from the racks and will bring about the return of the carriage in the manner explained. A tension spring 70 serves to hold the member 69 in the 35 position shown with relation to the two-armed member 65 and also serves to hold the lower end of member 65 against the bottom of cam 64. Clockwise movement of the member 69 (Fig. 9) upon the member 65 is permitted, if required, to 40 prevent blocking of the parts.

In order to cushion the return of the carriage to the left of the machine, an improved form of adjustable dash-pot is provided. (See Figs. 1, 2, 7, 8 and 11.) This includes a piston portion 45 71 rigidly secured to the frame of the carriage unit 48. The piston is adapted to enter a cylinder 72 integral with or otherwise carried by a sleeve 73 secured to the shaft 49. By securing the cylinder to the shaft in this way concentricity is insured between the cylinder and 50 piston. The one being secured to the shaft and the other slidably thereon a definite alinement is maintained. This is important inasmuch as the clearance between these relatively moving parts is very small. If an attempt were made to secure the cylinder to the frame member through which the sleeve 73 passes it would be difficult if not impossible to maintain concentricity between the cylinder and piston. The cylinder 72 is preferably formed of brass or similar resilient 55 material which at the same time is capable of being readily compressed. At its outer or right-hand end (Fig. 7,) the wall of the cylinder is considerably reduced, having a thickness of only about two hundredths of an inch. A steel band 74 is mounted around the outer end of the cylinder. This band is split and the two ends are brought together along a diagonal line 75, or a plane at an angle to the axis of the cylinder. (Fig. 8.) By means of a screw 76, the ends of the band may be brought more closely together or permitted to separate, as desired. Upon bringing the ends of the band together, the material of the cylinder will be compressed so 60 that its circumference or inside diameter will be

correspondingly reduced. In this way the air gap between the outer surface of the piston 71 and the inner wall of the cylinder may be varied to produce the desired cushioning effect. By arranging the ends of the steel band on a 80 diagonal line 75, as shown, the danger of causing the wall of the cylinder to buckle into the gap between the ends of the band will be avoided. Due to the resilience of the material of the cylinder it will expand again if the screw 76 is turned to free the grip of the band 74. By means of the improved construction there is, therefore, provided an adjustable dashpot action or cushioning effect between a non-rotatable piston secured to the sliding carriage and a rotatable or rockable cylinder carried by the shaft along which the carriage slides. 85 90

The operations of the various portions of the machine have been explained in connection with the detailed description. Repetition at this point is believed to be unnecessary. It should be observed, however, that the various improvements incorporated in the mechanism in accordance with the present invention all contribute to the speeding up of the operation 100 as a whole. The improved mounting of the escapement pawl makes it possible to oscillate the pawl and armature unit more rapidly than has heretofore been possible, without danger of loosening or breaking the parts. This enables 105 more rapid turning of the printing wheel from one character to the next. The improved construction and mounting of the printing wheel assembly permits it to be more readily shifted at letter space increments and permits rapid 110 rotation of the wheel for character selection without danger of misalignment of the printed characters. So also a more rapid return of the carriage upon completion of a line is made possible by the improved dashpot construction without 115 danger of injury to the parts. 120

While various features of the construction have been disclosed in considerable detail in relation to a particular type of printing mechanism, it will be understood that certain of these features may be considerably modified and may be used in other relations without departing from the general principles and scope of the invention as defined by the claims.

I claim:

1. In a telegraphic printer a character wheel, a supporting shaft therefor, said shaft having a keyway therein, a key rigidly secured to said wheel and adapted to enter said keyway, a second key movably mounted on said wheel and adapted to enter said keyway, and resilient means tending to shift said second key relative to said wheel.

2. In a telegraphic printer a character wheel, a supporting shaft therefor, said shaft having a keyway therein, a key rigidly secured to said wheel and adapted to enter said keyway, a second key movably mounted on said wheel and adapted to enter said keyway, and means for holding one of said keys against one side of said keyway and the other key against the opposite side of the keyway.

3. In a telegraphic printer a character wheel, a supporting shaft therefor, said shaft having a keyway therein, a pair of keys carried by said wheel and cooperating with said keyway, said keys being capable of relative angular movement, and tensioning means tending to produce such angular movement.

4. In a telegraphic printer a shaft, a charac-

ter wheel unit slidably mounted on said shaft, interengaging means on said unit and shaft for enforcing rotation in unison, said means permitting a slight play, means angularly movable upon said unit and interengaging with said shaft for rotation therewith, said last mentioned means being constrained for movement with said unit along the shaft, and tensioning means tending to produce angular movement of said 10 second mentioned means relative to said unit.

5. In a telegraphic printer a shaft having a keyway, a sleeve slidably mounted on said shaft, a character printing wheel mounted on said sleeve, means for clamping said wheel on said 15 sleeve, a key interposed between said clamping means and wheel, said key having a slight play in said keyway, a key angularly adjustable on said sleeve and having a similar play in said keyway, and a spring tending to produce angular 20 movement of said second mentioned key on said sleeve.

6. In a device of the class described a shaft, a carriage slidable on said shaft, spring means for shifting the carriage in one direction, and 25 a dash-pot for cushioning the movement of said carriage by the spring means, said dash-pot comprising a part secured to said shaft and co-axial therewith, and a part slidable along said shaft with the carriage and co-axial with said 30 shaft.

7. In a device of the class described a shaft, a carriage slidable on said shaft, means for shifting said carriage step by step in one direction and retaining the carriage in shifted position, means for returning the carriage when 35 released, means for rocking the shaft, means for releasing the carriage upon rocking the shaft, and a dash-pot including a part on the carriage surrounding the shaft and co-axial therewith 40 and a part fixed to the shaft and co-axial therewith, said parts being carried into and out of telescoping relation for cushioning the return of the carriage.

8. In a device of the class described a shaft, 45 a carriage slidable on said shaft, means for shifting said carriage step by step in one direction and retaining the carriage in shifted position, means for returning the carriage when released, means for rocking the shaft, means shift- 50 able with the carriage but rockable relative thereto upon rocking of said shaft for releasing the carriage, and a dash-pot including a part rockable with the shaft and a part held against rocking for cushioning the return of said carriage, said parts being carried into and out of 55 telescoping relation.

9. In a device of the class described a dash- 60 pot comprising a piston and a cylinder mounted on relatively movable parts, said piston entering freely into said cylinder, and adjustable means

for reducing the circumference of the cylinder to vary the cushioning effect.

10. In a device of the class described a dash- 65 pot comprising a piston and a cylinder movable into and out of cooperation, said cylinder being formed of resilient, readily compressible material, and adjustable means for compressing a portion of said cylinder to vary the circumference thereof.

11. In a device of the class described a dash- 70 pot comprising a piston and a cylinder movable into and out of cooperation, said cylinder being formed of resilient, readily compressible material, and a split band surrounding a portion of 75 said cylinder and adapted to compress the same to vary the circumference of said portion.

12. In a device of the class described a dash- 80 pot comprising a piston and a cylinder movable into and out of cooperation, said cylinder being formed of resilient, readily compressible material, and a split band surrounding a portion of 85 said cylinder and adapted to compress the same to vary the circumference of said portion, said band being split along a plane at an angle to the axis of the cylinder.

13. In a device of the class described a dash- 90 pot comprising a piston and a cylinder movable into and out of cooperation, said cylinder being formed of brass, a steel, split band surrounding a portion of said cylinder, and means 95 for contracting said band to compress said portion of the cylinder and vary its circumference.

14. In a device of the class described a dash- 100 pot comprising a piston and a cylinder movable into and out of cooperation, said piston and cylinder being rotatable relative to each other, and means for varying and setting the clearance between said piston and cylinder to regulate the dash-pot.

15. In a device of the class described a dash- 105 pot comprising a piston and a cylinder movable into and out of cooperation, the inside dimensions of said cylinder being slightly larger than the outside dimensions of the piston, one of said parts being formed of resilient material, and means for varying and setting the dimensions 110 of said one part to vary the clearance between the parts.

16. In a device of the class described a shaft, 115 a carriage slidably mounted on said shaft means for shifting said carriage to a predetermined position, and means for cushioning the carriage as it reaches said position, comprising a cylinder and a piston both surrounding said shaft and adapted to be moved into and out of telescoping relation, one being secured to said shaft 120 and the other mounted thereon and slidable with said carriage.
